(57) **CLAIM**

The ornamental design for an exhaust pipe end for a vehicle, as shown and described.

DESCRIPTION

This application is related to the following co-pending applications, of the inventor, filed on even date herewith: Application Ser. No. 29/271,454, entitled "Vehicle, Toy, and/or Other Replicas"; and Application Ser. No. 29/271,453, entitled "Vehicle, Toy, and/or Other Replicas".

FIG. 1 is a front view of a first embodiment of an exhaust pipe end for a vehicle according to my novel design;

FIG. 2 is a front view of a second embodiment of the exhaust pipe end for a vehicle according to my novel design;

FIG. 3 is a perspective view of the first embodiment of the exhaust pipe end for a vehicle according to my novel design;

FIG. 4 is a perspective view of the second embodiment of the exhaust pipe end for a vehicle according to my novel design; and,

FIG. 5 is an expanded front view of the first and second embodiments of the exhaust pipe end for a vehicle, providing a possible environment of the design.

The broken lines are for illustrative purposes only and form no part of the claimed design.
